COMBINED LIGHT AND CORD HOLDING DEVICE FOR PRESSING BOARDS

Filed Feb. 27, 1928

UNITED STATES PATENT OFFICE

THOMAS C. BALTHASER, OF KANSAS CITY, MISSOURI

COMBINED LIGHT AND CORD HOLDING DEVICE FOR PRESSING BOARDS

Application filed February 27, 1928. Serial No. 257,198.

This invention relates to a combined light and cord holding device for pressing boards or tables, on which an electric pressing iron having the usual electric cord connection is used, and has for its principal object the provision of an adjustable cord and light holding device carried by said board or table, and adapted to rotate together, thereby maintaining said light and pressing iron in proper relative positions.

Another object of the present invention is the contemplation of a combined light and electric cord holding device that will support the electric cord for the pressing iron so that it will be out of the way of the iron and the user, and at the same time will permit a free movement of the iron to and fro on the board.

A further object of the present invention is the provision of a device of the character described, in which a signal light is so positioned in the electric circuit with the pressing iron heat unit, that it will be lighted during the time that the iron is being heated.

Further objects of this invention are simplicity of construction, adjustability and durability.

With these general objects in view, as well as minor objects, which will appear during the course of the detailed specification, the invention will now be described with reference to the accompanying drawing, wherein

Figure 1, is a perspective view of a combined light and cord holding device for pressing board or table, shown in operative position on a pressing board, with some of the parts shown moved to a dotted position, embodying this invention.

Fig. 2, is an enlarged fragmentary view of the switch box and connecting parts with the closure removed and some of the parts broken away.

Fig. 3, is an enlarged fragmentary sectional view taken on line III—III of Fig. 1 with some of the parts omitted, and

Fig. 4, is a diagrammatic view of the electric wiring of the device.

Similar reference characters designate

like parts throughout the several views, and the numeral 5 designates a pressing board of the usual type, on which the present invention is mounted, however, this invention is well adapted for use on pressing tables where a greater range of adjustment is necessary. A stand 6, having a base 7 and a vertically extending spindle 8 is secured adjacent one end of the pressing board by means of screws or bolts 9. A vertically extending hollow standard 10 is fitted to and rotatably mounted on spindle 8 so as to be free to rotate to any position relative to said stand. The upper end of standard 10 is provided with a 3-way fitting 11, in the upper end of which is rigidly secured a horizontally extending hollow arm 12 having an ordinary electric light 13 attached to its outer end, which is provided with the usual cut-off switch 14. Any suitable reflector 15 may be carried by arm 12 in the usual manner, to properly distribute the light. Securely fitted to the 3-way fitting 11, is a socket 16, into which is fitted a removable plug 17 which is electrically connected to a flexible cord 18 adapted to conduct the electric current to a pressing iron 19. Said flexible cord is made sufficiently long to allow the iron to be moved to the extreme portions of the pressing board or table. A switch box 20 is securely attached to the hollow standard 10 adjacent its lower end, by means of the screw threads 21 at the lower end of said standard, engaging screw threads in said switch box and by a locking nut 22. With this construction, it is evident that when the standard 10 is rotated on the spindle 8, the switch box and light 13 will move through like angles. The switch box 20 is provided with a housing 23, having one of its sides open and a closure 24 adapted to securely close the open side of said housing. Pivotaly mounted to housing 23 at 25 is a socket member 26, which is normally held substantially parallel with standard 10, but is adapted to oscillate radially therefrom. Fitted in socket member 26 and extending upwardly therefrom, is a cord carrying extension arm 27 made of some suitable insulating material, 100

and having an insulating eyelet 28 at its upper end. As shown in Fig. 1, the cord 18 is positioned in said eyelet 28 in such a manner as to take up most of the slack cord between eyelet 28 and pressing iron 19. 5 Due to the relative sizes of the opening in the eyelet 28 and the cord 18, the eyelet and cord will be sufficiently secured together to cause the proper movement of the arm as hereinafter described. To normally maintain the arm 27 in the position shown in solid lines in Fig. 1, and yet allow it to oscillate to the position as shown in dotted lines, I have provided a coil spring 29 which 10 engages the socket member 26 adjacent its upper end, passes through an opening 30 in housing 23, and is secured to the opposite inner side of said housing at 31. To maintain that portion of the spring 29 within 15 said housing in its proper position as the arm 27 is oscillated, I have provided a guide roller 32, rotatably mounted and carried by the housing 23. As clearly shown in Fig. 2, the arm 27 is fitted into the socket member 26, and due to a reduction in diameter of arm 27 at 33 is thereby weakened, and should an undue strain be put on said arm, the tendency would be for it to break at the 20 point 33. Should this happen, arm 27 could again be fitted into socket 26 without materially affecting the operation of the device. Fitted on the socket member 26 and adapted to cover the joint between said socket member and arm 27 is a suitable cushion sleeve 25 34 which is so positioned as to engage the upper portion of housing 23 when arm 27 is being held in its normal position by means of the coil spring 29. The switch 35 which may be of any one of the well known 30 types adapted for this device, is securely mounted within housing 23, and has an operating means 36' extending through an opening in the closure 24. Positioned within the housing 23 is a signal light 36 which 35 is so positioned as to be in alignment with a bull's eye 37 securely mounted in the opening 38 in closure 24. The usual extension cord 39 for connecting this device with the ordinary house circuit extends through an 40 opening 40 in the lower side of housing 23 where the wires are separated and properly connected.

Since one of the objects of this device is 45 to provide a device of the character described, in which a signal light is provided in the circuit with the pressing iron, so as to indicate to the operator when the current is on the iron, for the purpose of preventing accidental fires and the use of unnecessary 50 current, a diagrammatic view of the circuit suitable for producing this result has been shown. In this circuit, 41 and 42 are the power feed wires through which the electric current is constantly flowing. 43 and 44 are 55 the wires of the extension cord 39 provided

with a switch 45. Wire 44 connects with one of the terminals of light 36 and is extended to one terminal of light 13. Wire 43 is connected with the other terminal of light 13. With this construction, it is apparent that whenever the switch 45 is closed, light 13 70 will be burning. Extending from the other terminal of signal light 36 is a wire 48 which extends to one of the terminals of the heating element 46 of the pressing iron. The other terminal of the heating element 75 46 is connected by wire 47 to wire 44 intermediate the light 13 and signal light 36. The switch 35 is so positioned that when closed it will connect wires 43 and 48 to close the circuit through signal light 36 and heat element 46. When switch 35 is open as shown in Fig. 4, no current will pass 80 through signal light 36 and heat element 46.

Hollow standard 10 and hollow arm 12 85 serve as conduits for a part of the electric wires used to carry the electric current for operating the lights and pressing iron.

I do not limit this invention to the structure shown and described, as many modifications may be made within the scope of 90 the appended claims without departing from the spirit thereof.

What is claimed as new and desired to be secured by Letters Patent is:

1. A device of the character described comprising a stand, a vertically disposed hollow standard rotatably mounted on said stand, a transverse light carrying arm carried by said standard, a switch box securely attached to said standard adjacent said stand and rotatable therewith, a cord carrying arm pivotally carried by said switch box and rotatable therewith.

2. A device of the character described comprising a stand having a vertically extending spindle, a hollow standard rotatably mounted on said spindle, a switch box secured to said hollow standard adjacent its lower end, a transverse arm rotatable with and carried by said hollow standard adapted to support a light, a cord carrying arm hingedly carried by said switch box and adapted to rotate therewith, and resilient means for maintaining said cord carrying arm in a substantially vertical position and permitting the arm to be oscillated.

3. The combination with an electric device and its conductor, of a stand, a standard having a transversely extending light-supporting arm rotatably carried by said stand, a conductor supporting arm hingedly carried by said standard adjacent its lower end and rotatable therewith, resilient means to normally maintain said conductor supporting arm in a predetermined position, and clamping means carried by said conductor supporter arm at its outer end for engaging said conductor to oscillate said conductor supporting arm.

4. The combination with an electric device and its conductor, of a stand, a standard having a transversely extending light-supporting arm rotatably carried by said stand, a switch box securely carried by said standard and rotatable therewith, a conductor supporting arm pivotally carried by said switch box, means for normally maintaining said conductor supporting arm in a predetermined position, and a signal light carried by said switch box and rotatable with said arm adapted to be lighted when the electric device is connected with the electric supply.
5. The combination of an electric device and its conductor, of a stand, having a vertically extending spindle, a hollow standard having a transversely extending light supporting arm rotatably carried by said stand, a box carried by said standard and securely attached adjacent the lower end thereof, a separable conductor supporting arm hingedly carried by said box at one side thereof and adjacent its bottom edge, a coil spring having one of its ends attached to said supporting arm intermediate its ends and its other end attached to the opposite side of said box, and a clamping means carried by the outer end of said supporting arm adapted to clampingly engage said conductor to oscillate said supporting arm.

In testimony whereof, I hereunto affix my signature.

THOMAS C. BALTHASER.
